J. D. GOSS.

DRESS HOOK.

APPLICATION FILED JAN. 23, 1919.

Patented Mar. 9, 1920.

Inventor

J. D. GOSS.

By *John Murphy Jr.* attorney.

UNITED STATES PATENT OFFICE.

JEFF D. GOSS, OF LAKE CITY, FLORIDA.

DRESS-HOOK.

1,333,483.

Specification of Letters Patent. Patented Mar. 9, 1920.

Application filed January 23, 1919. Serial No. 272,735.

To all whom it may concern:

Be it known that I, JEFF D. Goss, a citizen of the United States, residing at Lake City, in the county of Columbia and State 5 of Florida, have invented certain new and useful Improvements in Dress-Hooks; and I do hereby declare the following to be a full, clear, and exact description of the invention, such as will enable others skilled in 10 the art to which it appertains to make and use the same.

This invention relates to hooks and eyes and the primary object of the invention is to provide an improved hook and eye, in 15 which the parts can be readily attached together, and in which accidental displacement of these parts is eliminated.

Another object of the invention is to provide an improved hook and eye, in which 20 the hook and eye elements are adapted to be secured to tabs which are adapted to be detachably secured to the clothes of the wearer, so as to form a relatively wide attaching surface for the hook and eye elements and 25 thereby prevent tearing of the same from the garment of the wearer.

A further object of the invention is to provide an improved hook and eye constructed of resilient wire, the hook element 30 including two spring legs, the eye element having a means for engaging the legs to prevent relative movement of the same in relation to the eye, said means being arranged to diverge the legs to facilitate the 35 forcible attaching and detaching of the hook and eye element.

A still further object of the invention is to provide an improved hook and eye of the above character, which is durable and 40 efficient in construction, one that is simple and easy to manufacture and one that can be placed upon the market at a reasonable cost.

With these and other objects in view the 45 invention consists in the novel construction, arrangement and formation of parts, as will be hereinafter more specifically described, claimed and illustrated in the accompanying drawings, forming a part thereof, in which:

50 Figure 1 is an elevation showing a hook and eye applied to a garment,

Fig. 2 is a longitudinal section taken on line 2—2 of Fig. 1,

Fig. 3 is a plan view of the hook and eye 55 engaged,

Fig. 4 is a plan view showing the improved hook and eye separated,

Fig. 5 is a side elevation of the hook and eye engaged.

Referring to the drawings in detail, 60 wherein similar reference characters designate corresponding parts, throughout the several views, the numerals 1 and 2 indicate the hook and eye respectively. The hook 1 is formed of a single strand of resilient wire, 65 which is bent intermediate its ends to form an elliptical attaching base 3 and forwardly projecting parallel resilient legs 4 and 5 which lie in engagement with each other. The outer terminals of the legs 4 and 5 are 70 curved upwardly as at 6 and then outwardly in opposite directions to provide arcuate bills 7 and 8.

The improved eye is formed of resilient wire and it is bent intermediate its ends to 75 provide the spaced legs 9 and 10 which are converged adjacent to the inner end thereof as at 11 to provide a narrow neck 12. The legs are bowed outwardly in opposite directions from the converged portions 11 as at 13 80 and are then pinched together as at 14 and then curved to provide an elliptical attaching portion 15. The inner end of the eye 2 is bent back upon itself to provide a spaced parallel right angled portion 16, which terminates short of the diverged portions 11 of the legs.

The hook member 1 is adapted to be inserted in the bowed portions formed by the legs 13 and then drawn forwardly, so that 90 the bills 7 and 8 engage between the overlying portion 16 and the diverged portion of the legs.

A guard member 17 extends centrally of the eye and is formed of resilient metal and 95 has the inner end thereof attached to the central portion of the overlying portion 16 of the eye. The outer end thereof is coiled around the diverged portion 14 as at 20 which holds the guard member against displacement. The guard member 17 is bent downwardly as at 21 adjacent to the restricted neck portion 12 and extends rearwardly therefrom and is positioned substantially in alignment with the bowed portions 13 of the legs 9 and 10. The bent portion 21 is arranged to engage directly between the legs 4 and 5 of the eye 1 so as to prevent accidental displacement of the hook from the eye when the same are attached. 105 110

In operation of the improved device, the hook 1 is inserted between the bowed portions 13 of the legs 9 and 10 of the eye and forced slightly upwardly so that the guard member 17 will tend to spread the legs 4 and 5 of the hook. The hook is then pulled forwardly so that the bills 7 and 8 engage over the legs 9 and 10 of the diverged portions 11 thereof and is pulled forwardly until the bills engage the overlying portion 16. The guard member, as stated, prevents accidental displacement of the hook and eye and when it is desired to disengage the hook 1 from the eye, the hook is moved rearwardly until the guard member is positioned between the legs 4 and 5 which diverges the same and allows the legs to be slid over the guard member until the same reaches the bowed portions 13 of the legs 9 and 10, at which time the hook can be removed from the eye.

The elliptical attaching portions 3 and 15 of the eye 2 and hook 1 are adapted to be inserted between the plies 22 and 23 of substantially square tabs 24 and are secured thereto by means of thread or the like 25. The tabs form an enlarged base whereby the hook and eye may be readily placed in position. The tabs are adapted to be secured at each corner thereof to the garment by means of thread or the like and are to be removed when the garment is to be washed so as to prevent rusting of the eyes and thus disfiguring the garment. The tabs as stated also form a large attaching portion for securing the hook and eye to the garment and thus prevent the tearing of the garment under excessive strain.

In practice, I have found that the form of my invention, illustrated in the accompanying drawings and referred to in the above description, as the preferred embodiment, is the most efficient and practical; yet realizing the conditions concurrent with the adoption of my device will necessarily vary, I desire to emphasize the fact that various minor changes in details of construction, proportion and arrangement of parts may be resorted to, when required without sacrificing any of the advantages of my invention as set forth.

What I claim as new is:—

1. A hook and eye device comprising hook and eye members, the hook member having a pair of diverging arcuate bills, the eye member being bent to form means for re-

ceiving the bills, and a guard carried by the eye to prevent accidental displacement of the bills.

2. A hook and eye device comprising hook and eye members, the hook member including a pair of arcuate oppositely arranged bills, the eye member including a pair of spaced legs, the inner portion thereof being converged and bent back upon itself to receive said bills, and a guard member arranged centrally of the legs of the eye member to prevent accidental displacement of the bills.

3. A hook and eye device comprising hook and eye members, the hook member including a pair of resiliently connected parallel legs, arcuate oppositely disposed bills formed on the terminals of the legs, the eye member including a pair of spaced legs having the inner terminal thereof converged and bent back upon itself to receive the bills, and a guard member extending longitudinally of the eye and arranged centrally of the same, said guard member having the central portion thereof bent downwardly and positioned between the converged portion of the legs to prevent accidental displacement of the bills, said guard member forming means for spreading the resiliently connected legs whereby the same may be readily removed and attached to the eye.

4. A hook and eye device comprising hook and eye members, each including enlarged elliptical attaching eyes, the hook including a pair of resiliently connected legs, arcuate bills disposed in opposite directions and formed on the terminals of the legs, said bills being bent upwardly and arranged in a plane above the legs, the eye member including a pair of spaced legs, said legs including centrally disposed portions and converging terminals, the inner terminal being bent back upon itself, a resilient guard member extending centrally of the eye and having the terminals thereof secured to the legs, said guard member having a centrally bent portion arranged intermediate the diverged portion of the legs and said bent portions forming means for preventing the accidental displacement of the bills.

In testimony whereof I affix my signature in presence of two witnesses.

JEFF D. GOSS.
